METHOD AND APPARATUS FOR MARKING
MOLDED BUILDING BLOCKS

Herbert F. Geist, Cleveland, Ohio

Application June 27, 1942, Serial No. 448,792

12 Claims. (Cl. 101—126)

This invention is concerned with the art of manufacturing building blocks of the molded concrete type and the general object thereof is the provision of a novel method of applying trademarks, dates, names, etc. to concrete blocks in such a manner and at such particular time in the course of manufacture of the block that the applied insignia will serve its purpose until the marked block becomes incorporated in a building structure.

Another object of the present invention is the provision of a novel simple block marking apparatus which is adaptable to ready association with concrete block molding machines, conveyors and drying racks and utilizable for the purpose of applying the marking in the preferred form by a stencil spray operation upon the green block without necessitating extra handling of the green block.

In the concrete building block industry the block is usually formed in a molding machine which is suitably designed and operable to perform the major molding operation through a vibrating or jolting action upon the mix or agglomerate charged into the mold. A finishing pressure is applied to shape the agglomerate or mix within the mold to a uniform size and to finish the top of the block. This vibrating and nominal or low pressure molding method produces blocks with desired tensile and compressive strengths, density, and sameness of dimension in a highly productive manner. The green blocks, while supported on or carried by pallets, are removed from the discharge end of the molding machine after the blocks have been stripped from the molds. The green blocks are handled with appropriate care while in this green state to prevent marring and deforming of the block. The blocks supported on pallets are usually removed from the molding machines by a conveyor which transfers the same to a drying rack.

In many locations building codes or regulations exist which require that the date of manufacture of the block and other data be carried by the block and such codes usually require a minimum ageing period before the block can be incorporated in a building structure. These ageing periods may vary but are substantially of a duration of thirty days.

It is also the general practice to subject the green block after it has been removed from the molding machine, to a wet steam drying treatment to control the rate of setting of the cement, and this wet drying step may vary in duration depending upon the ideas of the block manufac-

turer and the particular size and shape of the block, but in any event this wet drying period is for a duration of not much less than twenty-four hours.

5 Various ways of applying markings to a concrete block have been followed heretofore, such, for example, as the actual molding of the marking into the top or under surface of the block. In other instances manual chalk marking has 10 been utilized. Both of these methods of marking have their drawbacks in that if the marking is effected in the molding operation the cost of the molding equipment is increased and the particular location of the marking is confined to the top or bottom surface of the block so as not to interfere with the stripping action of the molding machine. Chalk marking has been found to be 15 unsatisfactory due to the fact that the markings become smeared or obliterated, and such markings cannot be applied to green blocks with any 20 degree of permanency.

By my present method I propose to apply the marking to the green block immediately after the block has been formed in the molding machine and stripped from the mold by the machine 25 and I apply such a marking by a stencil spray operation on one of the bonding faces of the block. Such marking is effected by the utilization of a colored aqueous mix of sufficient body 30 to pass through a spraying machine but sufficiently dense to quickly form the desired marking by stencil outline. This material is such that it will bond to and penetrate to some extent into the relatively porous surface of the block. The 35 materials used should be such as to not discolor to any undesirable or substantial degree during the wet drying operation to which the green block subsequently is subjected. The applied marking can, of course, comprise the name of the manufacturer, or the trade-mark of the manufacturer 40 or other trade-marking as well as the required date of manufacture.

Other objects of my invention may become 45 apparent from the following description and by referring to the accompanying drawings showing the manner of carrying out the steps of my method of applying the insignia to the green block and also showing several forms of an apparatus suitable for carrying out the steps of my 50 novel method.

In the drawings:

Fig. 1 is a side elevation of a green block molding machine of a commercially available type having adapted thereto a pneumatically operated 55 green block conveyor mechanism and an asso-

ciated spray marking mechanism which will permit of the labeling of the block in the manner desired during the manufacturing step of transferring the green block from the discharge end of the molding machine to a drying rack or conveyor;

Fig. 2 is an enlarged elevation of the block or pallet supporting end of the conveyor mechanism of Fig. 1;

Fig. 3 is a top sectional view of the mechanism shown in Fig. 2 taken substantially along the line 3-3 of Fig. 2;

Fig. 4 shows the block supporting end of the conveyor mechanism of Figs. 1 and 2 as viewed from the operator's side of the conveyor mechanism;

Figs. 5 and 6 are fragmentary top views of two positions of a stencil and support therefor relative to the nozzle of the spray apparatus;

Fig. 7 is a modified form of a stencil supporting means;

Fig. 8 is a second form of the embodiment of the apparatus of my invention adaptable to the discharge end of the green block molding machine whereby the marking can be applied to the block before the block leaves the discharge end of the molding machine and Fig. 9 is an end view of the same.

My invention contemplates the incorporating of a block marking apparatus into a conveyor mechanism which is associated with the block molding machine of the type hereinbefore referred to. This marking apparatus can be installed at the block discharging end or side of the molding machine or with the chain conveyor or slide mechanism of the molding machine. The first example of embodiment is arranged in such a manner that when the conveying mechanism (usually also a pallet and block elevating mechanism) is being used to transfer the green block or blocks from the discharge end of the molding machine to a drying rack or a conveyor extending to a drying kiln, the operator can manipulate a spray gun control disposed adjacent the operator's control for the conveyor elevator mechanism. Thus, it permits a spray marking of the green block while the block is on a pallet resting on the support of the conveying and elevating mechanism.

In the drawings in Fig. 1 a general outline of a block molding machine is illustrated together with an elevational view of a green block conveying and elevating mechanism.

Machines of the general type shown in Fig. 1 are arranged to automatically feed steel plates or pallets into and through the machine by a feed mechanism, not shown, but will be referred to hereinafter as a chain conveyor indicated by the dash line 4 in Fig. 1. The conveyor 4 travels from rear to front or discharge side of the machine frame 5. At the rear of the machine a stack of pallets P are arranged in decked or stacked fashion in a holder or magazine 6. One pallet at a time is slid or removed from the bottom of the stack by lugs on the chain conveyor 4 and advanced to a molding position or station in the front part of the machine. At the molding station suitable mechanism elevates the pallet out of engagement with the chain conveyor lugs and positions it against the bottom of an open mold box, to thus constitute the bottom wall of the mold. Core members (not shown) are then lowered into the mold box into contact with the pallet top surface. Agglomerate or mix is then charged into the mold box whereupon the pallet

and mold box are subjected to a vibratory or jolting action to cause the agglomerate to uniformly settle within the confines of the mold and about the cores. A pressure or stripper head is then lowered downwardly into contact with the jolted or vibrated agglomerate within the mold to exert a nominal pressure upon the agglomerate and to finish the molding action of the machine by leveling the top of the agglomerate within the mold and to complete the formation of the block to the desired height. The green molded block is then stripped from the mold by holding the pressure or stripper head stationary while the core members and the mold box are simultaneously elevated, thus leaving the shaped green block upon the pallet. Thereafter, the pressure member is elevated away from the green block or the green block and pallet are lowered away from the pressure head and the pallet and block are shifted away from the molding station of the machine to the discharging end thereof. Such a machine is generally indicated in the side elevation in Fig. 1.

The green block conveying and elevating mechanism may be of several forms, the particular form shown in the drawings being of the swingable boom type supporting a pneumatically operated elevator mechanism.

The boom member comprises a pair of channel members 15 disposed with the flanges thereof extending inwardly and carried by a pivotally mounted mast 16 suitably supported on the frame of the molding machine as shown by a base member 17 and tie brackets 18. The mast may be otherwise supported, if desired. A bottom truss member 19 and vertical struts 20 interconnected by diagonal struts 21 complete the track structure for a conveyor carriage 22.

As shown the conveyor carriage 22 is supported on the flanges of the channels or track members 15 by carriage wheels 23 riding on the flanges of the members 15.

Fixed to and dependent from the carriage 22 is a piston rod 24 upon the lower end of which is a pneumatically operated piston member (not shown) disposed within the pneumatic cylinder 25. Secured to the lower end of the cylinder 25 is a green block supporting structure comprising an L-shaped frame and members which extend horizontally away from the bottom of the cylinder 25 and then downwardly to be connected to a horizontally disposed load support 28. The load support may be forked shaped if desired and so designed that it may be disposed under a pallet or pallets carrying a green block or green blocks stationed at the discharge end of the machine. Strut members 27a extending between the frame members 27 and the load supporting structure or platform 28 add rigidity to the load engaging and supporting means 28.

A pneumatic control for regulating the volume of air under pressure within the cylinder to bring about relative movement between the elevator rod 24 and cylinder 25 may comprise a flexible air conduit 30 from a source of compressed air and which extends downwardly along the cylinder to a piping and controller valve system carried by the frame structure 27-28.

The piping is arranged so that the valves can be operated to admit compressed air into the cylinder and permit the compressed air to escape therefrom as desired. Thus the supply line is connected to a branch 32 leading to a trigger valve mechanism 33 operated by a controller handle 34 disposed to the left of the operator's position as

shown in Figs. 3 and 4. When the controller lever 34 is operated the elevator mechanism is raised by pneumatic pressure exerted in the upper part of the cylinder by the passage of compressed air through the conduit 31. A second conduit branch 36 leads to a controller valve 31 operated by controller lever 38 disposed on the left side and which, when operated, causes the elevator mechanism to lower due to the ingress of compressed air through conduit 31a into the lower part of the cylinder.

Connected into the pressure side of the described piping system is a flexible conduit 40 leading to a spray gun apparatus 41 and suitably attached to the frame comprising the work support of the conveying and elevating mechanism with the nozzle 41a thereof positioned to spray in the direction of a green block when on the elevator platform of the conveyor.

Mounted upon the frame structure of the elevator is a bracket member 43 upon which are swingably mounted a pair of link members 45 which support or suspend a stencil plate or membrane 48 adjacent one surface of a green block when the block is raised on a pallet supported by the conveyor mechanism. In the arrangement shown in Figs. 5 and 6 a stencil 48 is swung through a slight distance into contact with the end of the block upon the first impact of pigmented material projected by the spray gun to cause the stencil to swing to the position shown in Fig. 5. When air pressure on the gun is shut off the stencil then falls to the position shown in Fig. 6 under the influence of gravity.

In Fig. 7 I have shown a modified form of support for the stencil 48 which comprises a frame structure 50 suitably secured to the load support with the stencil 48 yieldingly supported on the frame 50 by four sensitive spring members 51. The stencil will be brought into the spraying position illustrated in Fig. 7 at the time the conveyor mechanism is being manipulated at the discharge end of the molding machine to engage the pallet with the green block thereon, to thus have one surface of the block juxtaposed or in contact with the stencil and thus cause slight compression of spring members 51. The stencil will remain in the position illustrated in Fig. 7 as long as the pallet and the green block are on the work support of the conveyor. The connections for the spray gun 41 in this modified form may be substantially the same as thus illustrated in Figs. 1, 2, 3 and 4.

In Figs. 8 and 9 I have shown a duplex marking apparatus associated with the discharge end of a molding machine whereby suspended stencils may be swung against the faces of a pair of green blocks while the spray marking is being effected. Fig. 8 is a side elevational view of a molding machine discharge end having a pallet carriage 60 suitably supported by an upwardly extending frame structure comprising side channel members 61 attached at the inner ends thereof to the uprights 62 of the frame of the machine. The channel members 61 are suitably braced by horizontal spacer members and diagonal braces 64. Angle irons 65 are mounted on the tops of the channel members to constitute rails upon which the wheels 60a of the carriage 60 ride. As shown, the carriage 60 is of sufficient width to support the pallet P while carrying two blocks.

Disposed at each side of the framework supporting the carriage rails are stencil supports 68 of any suitable structure to conveniently suspend the stencil members 70 in juxtaposed relation to faces of the blocks while on the carriage. The members 68 may be U-shaped as shown with the

lower ends thereof attached to the channel members 61. The stencils may be swingably suspended thereon by ring members 72.

The spray marking mechanism may comprise a control system arranged at each side of the carriage effecting simultaneous operation of both marking apparatuses. This arrangement is as follows. An air line from a suitable source is connected to a pressure regulator 75. The regulator is suitably supported by a plate 73 secured to one of the channel members 61 and to one of the machine frame members 62. The regulator is connected to an air control valve 76. This valve is operated by lever 80, depending rod 81 and treadle lever 82, there being a spring member 83 which serves to maintain this valve operating mechanism in position to maintain the air valve 76 normally closed.

A spray gun apparatus 78 is supported on the member 68 by a cross-bar 79 and to which it is secured with the nozzle of the gun in an operative position to shift or swing the stencil against the face of the block during the spraying operation. The gun is connected to the air line by a flexible conduit 81.

The arrangement for the opposite side of the machine for mounting the gun, stencil, etc., is substantially the same as described and a connecting line, extending from the valve control side of the machine to the opposite side thereof, is connected to the spray gun apparatus 88 by a conduit 87.

The foregoing described arrangement permits of the simultaneous marking of the blocks immediately after the removal thereof from the molding machine.

As a further example of the adaptability of the disclosed marking apparatus and particularly the form shown in Fig. 7, portability can be obtained by simply using the marking apparatus independently of the conveyor mechanism or the molding machine. The operator can carry the combined stencil and spraying apparatus from block to block when the same are on racks or conveyers, and manually compress the stencil and springs 51 against a base of a block before releasing the spraying blast. Such marking can be effected on either dried or green blocks.

While I have disclosed two embodiments of an apparatus for carrying out the novel steps of marking a building block of the particular molded type while in a green state and whereby such marking can be effected without unduly increasing the production cost of the block, it is to be understood that such disclosure is not by way of limitation of the scope of the invention except as set forth in the appended claims.

Having thus described my invention, I claim:

1. In the art of manufacturing molded building blocks by the use of molding and stripping machines, the step of labeling the block immediately after the block has been stripped from the mold comprising stencil spraying the label upon a bonding face of the block with coloring matter carried in an aqueous vehicle and while the block is still wet and thereafter drying the stenciled label simultaneously with the block by placing the same in a moisture saturated drying kiln.

2. In the art of manufacturing molded building blocks, the step of labeling the block after the block has been extracted from the mold and while in a green condition by stencil spraying the label upon a bonding face of the block while the block is in transit from the mold to a drying

station to thereby eliminate extra handling of the green block during labeling operations.

3. In the art of manufacturing molded building blocks, the step of labeling the block while the block is in a green condition comprising stencil spraying the label upon a bonding face of the block while the block is in transit from the mold to a drying station to thereby eliminate extra handling of the green block during labeling operations.

4. The method of applying insignia, such as trade names, dates, etc., to a building block of the molded type comprising forming the legends on the bonding face of the block by spraying colored matter onto said face through a stencil while the block is in a green or undried condition and during the conveying of the block from the mold to a drying station.

5. In apparatus of the character described, the combination with a concrete block conveying mechanism for transferring a green molded block from a molding machine to a drying rack or conveyor, including a support for the green block to be conveyed, of a block marking mechanism mounted upon the conveying mechanism in juxtaposition to the said support to thereby be adjacent to a surface of a green block when on the support, and controller means disposed to be available to the conveyor operator for ready operation of the block marking mechanism while the green block is being transferred from the molding machine to a drying rack or drying conveyor.

6. In apparatus of the character described, the combination with a pneumatically operated concrete block conveying mechanism for transferring a pallet carrying a green molded block from a molding machine to a drying rack or conveyor, including a support for engaging the under side of the pallet of a block spray marking mechanism mounted upon the conveying mechanism in juxtaposition to the said support to thereby be adjacent to a surface of a green block on the pallet being conveyed, a pneumatic controller on the conveyor for operating the conveyor mechanism and controller means disposed adjacent the pneumatic controller to be available to the conveyor operator for ready operation of the spray marking mechanism while the green block is being transferred from the molding machine to a drying rack or drying conveyor.

7. In apparatus of the character described, the combination with a concrete block conveying and elevating mechanism for removing a green molded block on a pallet from a molding machine, having a support for the pallet of a block marking mechanism mounted upon the conveying mechanism in juxtaposition to a surface of a green block when on the conveyor, controller means disposed to be available to the conveyor operator for ready operation of the block marking mechanism while the green block is on the conveyor, a common power applying means for operating the elevating mechanism and the block marking mechanism, there being arranged adjacent the first said controller means a second controller means for operating the elevating mechanism.

8. In apparatus of the character described, the combination with a concrete block conveying a pneumatically operable elevating mechanism for removing a green molded block on a pallet from a molding machine having a support for the pallet of a spray gun block marking mechanism, including a stencil mat, mounted upon the conveying mechanism in juxtaposition to a surface of

a green block when on the conveyor pneumatic controller means for the spray gun marking mechanism disposed to be available to the conveyor operator for ready operation while the green block is on the conveyor, a common pneumatic power applying means for operating the elevating mechanism and the block marking mechanism, there being arranged adjacent the first said controller means a second controller means for operating the elevating mechanism.

9. The combination of a conveyor mechanism for green concrete blocks having a horizontally extending support for uniformly supporting a green molded block, a stenciling apparatus operably mounted upon the conveyor mechanism for effecting a stencil marking upon a green block positioned upon said support including a perforated stencil movably mounted upon the conveyor mechanism adjacent the block support whereby the stencil can be positioned against a surface of the block and a spray gun apparatus carried by the conveyor mechanism with suitable controls therefor disposed adjacent the operator's side of the conveyor mechanism.

10. The combination of a conveyor having a pneumatically operated elevator mechanism provided with a horizontally extending work support for engaging the underside of a pallet supporting a green molded block, a stenciling apparatus operably mounted upon the work supporting structure of the elevator mechanism for effecting a stencil marking upon a green block resting on a pallet positioned upon said support including a perforated stencil movably mounted upon the elevator mechanism adjacent the block support whereby the stencil can be positioned against a surface of the block and a spray gun apparatus carried by the conveyor mechanism, conduit means connecting the spray gun to the source of pneumatic pressure for the elevator mechanism and a suitable pneumatic controller therefor disposed adjacent the operator's side of the conveyor mechanism.

11. In the art of manufacturing molded building blocks by the use of a molding machine, the step of labeling the block with insignia, such as trade names, dates, etc., after the block has been stripped from the mold and before any substantial drying thereof has taken place comprising stencil spraying the label upon a bonding face of the block with coloring matter in liquid form and while the block is still undried and thereafter drying the stenciled label simultaneously with the drying of the block.

12. In apparatus of the character described, the combination with a concrete block molding mechanism including means for removing a green molded block on a pallet from the molding machine having a support at the discharge end of the machine for the pallet, of a block marking mechanism mounted in juxtaposition to the said support to thereby be adjacent to a surface of a green block when on a pallet resting on the support, said block marking mechanism comprising a spraying apparatus and a movably mounted stencil stationed adjacent said pallet support and controller means disposed to be available to the operator for convenient operation of the block marking mechanism while the green block and pallet are on the support where insignia such as trade names, dates, etc., can be applied to a bonding face of the block while the block is in a green condition.

HERBERT F. GEIST.
